UNITED STATES PATENT OFFICE

2,453,369

PIPE TONGS

Donovan B. Grable, Long Beach, and John M. Jackson, Santa Monica, Calif.

Application May 15, 1945, Serial No. 593,870

9 Claims. (Cl. 255—35)

1

This invention relates generally to improvements in tongs for making and breaking threaded joints between sections or stands of well pipe. In certain and more particular aspects, the invention contemplates improvements in the type of combined tongs and pipe spinner disclosed in the Grable Patent No. 2,311,225 issued February 16, 1943, on Pipe rotating apparatus.

One of the major objects of the present invention is to provide a novel self-powered tongs assembly characterized by its employment of relatively rotatable gripping means or jaws adapted to engage the pipe string at both sides of the joint, and operable to produce relative rotation of the gripping means in either direction for making up or breaking the joint, as the case may be. In this connection, the invention contemplates constructing the tongs body with relatively rotatable sections, each carrying individual pipe gripping means and preferably individual power units for operating the gripping means, and incorporating in the assembly another power unit having such relation with the body sections that controlled and selective operation of the unit produces opposite relative rotations of the sections.

Another object and feature of importance is the provision of an improved power-driven spinner mechanism for rotating one of the pipe sections independently of the aforesaid gripping means in the operation of taking up a loose joint to snug condition, preparatory to final tightening by relative rotation of the body sections and gripping jaws, or disengaging the joint after initial loosening by the body section and jaw rotation. In serving the purposes of the invention, the spinner and its motor have novel association with the upper tongs body section and the jaw actuating power units, all in a manner permitting predetermined sequential application or release of the spinner and jaws with relation to the pipe.

Contemplated also is the use of fluid pressure actuated power units, all driven by high pressure fluid from a single source, for operating the spinner motor, the jaw actuating power units, and the power unit by means of which relative rotation of the body sections is effected in making up and breaking the joint. As will appear, the invention includes the provision of a simple valve assembly, conveniently mounted on the tongs body, for selectively controlling the operation and communication of pressure fluid to the several power units.

Various additional features and innovations might preliminarily be recited at length, but all these, as well as the features and objects referred to above will be explained to best advantage in

2

the following description of the typical and illustrative embodiment of the invention shown in the accompanying drawings, and in which:

Fig. 1 is a perspective view of the tongs assembly applied to the pipe string at a joint;

Fig. 2 is a longitudinal vertical sectional view of the tongs assembly;

Fig. 3 is a cross-section on line 3—3 of Fig. 2;

Fig. 4 is an end view taken from line 4—4 of

10 Fig. 2;

Figs. 5 and 6 are fragmentary vertical sections taken on lines 5—5 and 6—6 of Fig. 2 through the spinner and tongs section mechanisms;

15 Figs. 7 and 8 are horizontal sections taken on lines 7—7 and 8—8 of Fig. 2; and

Fig. 9 is a diagrammatic illustration of the control valve mechanism and its connections with the swivel power units.

Referring mainly to Figs. 1 and 2, the tongs 20 assembly is shown to comprise a body structure, generally indicated at 10, including upper and lower relatively rotatable sections 11 and 12. The general form and construction of the sections may be given any suitable design adaptable for 25 accommodation of the various working parts. Typically, the upper section 11 may comprise vertically spaced members 13 and 14 interconnected by channels 15 and 16, the end portions of 30 which toward the pipe 16 are deformed outwardly as at 17, see Fig. 6, for purposes that will later appear. To the right of member 13, the channels 15 carry a pair of members 20 to which is secured the housing or cover 21 for the pipe spinner and 35 motor assembly generally indicated at 22. The lower tongs section 12 similarly comprises spaced members 23 and 24 interconnected by channels 25, the latter having outwardly deformed portions 26 similar to and serving the same later 40 described purposes as portion 17 of the channels and the upper tongs section.

One of the channels 15 of the upper body section extends at 15a part way about the pipe 16, the corresponding channel 25 of the lower section 45 similarly being extended at 25a about the pipe. The channel portion 15a carries a body or support 27 within which the pipe gripping dies or jaws 28 are retained. The lower channel portion 25a carries a pair of supports 29 and 30 each 50 containing the gripping dies 31, the support 30 being mounted for movement radially with relation to the pipe. Such movement is permitted by mounting the support 30 on pin 31 extending through the bossed portion 32 of the channel, coil spring 33 tending to thrust the die toward the

pipe a distance permitted by the engagement of the pin head 34 with the boss.

The body sections 11 and 12 have at 35 a swivel connection permitting their relative rotation about the pipe axis. The swivel connection is shown to comprise typically a ring segment 36 secured to member 23, and segments 37 and 38 secured to the underside of member 14 in interfitting and interlocking relation with the segment 36. Roller bearings 39 may be employed to facilitate relative rotation of the sections.

The upper tong section 11 contains a reciprocable jaw mount or body 40 confined and guided within the ways 41, see Fig. 6, below the guide channels 42. The body 40 carries at its inner face the support 43 and jaw inserts 44. The body and jaw assembly is reciprocally operated by a power unit 45, preferably of a piston and cylinder type, the piston rod 46 having an end portion 46a pivotally connected to the jaw body pin 47. At a certain position in the later described operating sequence, movement of the jaw body and piston rod in a pipe engaging direction is resisted by coil spring 48 confined between the rod flange 49 and bracket 50 attached to and depending from the underside of a spinner mechanism carriage 51. As will be understood, the cylinder of the power unit 45 is stationarily affixed by suitable means to the body section containing it.

The lower body section 12 similarly contains a piston and cylinder power unit 52, the piston rod 53 having a direct pivotal connection at 54 with the jaw body 55, the latter being reciprocally guided within the side portions of the body section in a manner similar to the mounting and guiding of upper jaw body 40, as will be apparent from Fig. 6 without necessity for further illustration.

A suitable power unit, generally designated at 56, see particularly Fig. 5, is provided in interconnected relation with the upper and lower tong sections for positively producing relative rotation of the sections in opposite directions in the operations of making up or breaking the pipe joint. The power unit 46 also may be of a piston and cylinder type, comprising a cylinder 57 secured at 58 to the upper body section 11, and a piston 59 having a pivotal connection at 60 with bracket 61 secured to the lower body section 12. As will be apparent, upon relative reciprocation of the cylinder 57 and piston 59 in opposite directions, the tong body sections and their respective pipe gripping jaws are caused to rotate relatively in opposite directions.

The spinner mechanism 22 comprises a spinner wheel 62 having a suitable anti-friction pipe engaging surface, the wheel trunnion 63 being journaled within suitable bearings 64 for rotation within portion 51a of the carriage overlying the wheel. The latter is rotatably driven by a fluid motor or turbine 65 affixed to the carriage 51, the motor shaft 66 carrying a bevel gear 67 engaging ring gear 62a carried by the spinner wheel 62. Carriage 51, and therefore the spinner wheel and motor assembly, are movable radially of the pipe 16 and relative to the body section 11, the carriage 51 for this purpose being mounted for reciprocation within guide ways 70 in members 20, see Fig. 5. Being attached to the underside of the carriage, bracket 50 travels with the carriage in its reciprocal movements.

Pressure fluid, e. g. compressed air, supplied to and exhausted from the apparatus respectively through lines 71 and 72, is controlled in its communication to the cylinders 45 and 52, the power

unit 46 and the spinner motor 65, by a valve assembly 73, see Fig. 1, which may be mounted on either body section, for example the side flange of the lower section 12, as illustrated. As best 5 shown by the piping diagram in Fig. 9, the valve assembly 73 comprises individually operable three-way valves 73, 75 and 76 with their control handles 78, 79 and 80. The showing of the control valves need be diagrammatic only since 10 three-way valves suitable for this type of control are well known and require no specific illustration. Valve 74 controls the delivery of pressure fluid from line 71 to the cylinder 57, and the fluid exhaust therefrom to line 72, selectively through lines 81 and 82. The pressure fluid supplied to 15 and exhaust from cylinders 45 and 52 similarly is controlled by a suitable valve mechanism 75 through lines 83 and 84 individually connecting with opposite ends of the cylinders as illustrated. Valve 76 controls the communication of pressure fluid to the spinner motor 65, and the exhaust therefrom, selectively through lines 85 and 86. As 20 will be understood, the control by valves 74 and 75 permits positive operation of the pistons in cylinders 45, 52 and 57 in either direction, and valve 76 permits positive reverse operations of the 25 spinner motor 65.

As indicated, the relatively high fluid pressure communicated through line 84 to the cylinders 45 and 52, is sufficient to bring the jaws and dies into 30 gripping engagement with the pipe, against the resistance of springs 48, 33 and 91. To facilitate operation of the spinner 62 to rotate the upper pipe stand while the gripping jaws and dies remain disengaged from the pipe, we preferably incorporate in the control system, means for selectively actuating the spinner carriage 51 under sufficient pressure to contact the spinner 62 against the pipe, but without advancing the pistons 46 and 53 distances sufficient to cause the 35 jaws and dies to grip the pipe. Referring to Fig. 9, the valve mechanism 75 is adapted to selectively supply the high pressure fluid through line 75a to a pressure regulator 75b, the discharge from 40 which occurs through check valve 75c and into line 84. It will be understood that in practice, the pressure regulator and check valve may be incorporated within the control valve mechanism 75 as one unitary structure. The effect of the pressure 45 regulator 75 is to permit communication to the cylinders 45 and 52 of pressure sufficient to contact the spinner 62 against the pipe, but insufficient to overcome the resistance of springs 48, 33 and 91 to the extent of bringing the jaws and dies into gripping engagement with the pipe. As will be understood, during advancement of the pistons and cylinders 45 and 52 under the lower or 50 regulated pressure, fluid is displaced by the pistons through line 83 to the discharge line. At other times, when the high pressure fluid is delivered to the cylinders through line 84, check valve 75c prevents back-flow of the high pressure fluid to the regulator.

In considering the operation of the invention, 55 assume the tong assembly to have three-point suspension on the cables 87 and to be applied to the pipe 16 with the jaw bodies 43, 43a positioned respectively above and below the ends of the pipe stands which are to be screwed together to the joint line J. Assume also that the lower stand is held by the usual table slips, and that the upper stand has been lowered in position to be screwed onto the lower stand. As the tongs are initially 60 placed about the pipe the jaw body 30 and its dies 31 are thrust inwardly by coil spring 33 a distance

sufficient to prevent engagement of the pipe with the jaws carried by the supports 27 and 29. The pipe also will be free from gripped engagement with the dies carried by supports 43 and 43a. The pipe is supported diametrically opposite the spinner wheel 62 by rollers 88 carried by yoke 89 supported on pin 90, the roller and yoke assembly being urged toward the pipe by coil spring 91.

First the spinner motor 65 is started in operation and relatively low fluid pressure is communicated through line 75a to cylinders 45 and 52, to simultaneously advance the jaw mounts 40 and 55 toward the pipe a distance sufficient to engage the spinner wheel 62 against the upper pipe stand (movement of piston 46 being transmitted through spring 48 to the spinner carriage assembly) but without yet permitting gripping engagement of the dies 44 with the pipe. Upon contacting the pipe, the spinner wheel turns the upper stand in the proper direction to take up the joint to a more or less snug condition thereupon. By operation of the lever 79, the valve mechanism 75 is caused to admit high pressure fluid through line 84 to the cylinders 45 and 52 (fluid delivery through line 75a being discontinued) to cause the dies 44, 28 and 44a, 31 to grip the pipe. Valve 74 now is operated to actuate the piston and cylinder assembly 56 to produce relative rotation of the tongs sections 11 and 12 in a direction producing tightening rotation of the upper pipe stand and complete make-up of the joint J. During the advancement of the pistons and cylinders 45 and 52, fluid is displaced from the low pressure side of the pistons through pipe 83 to the discharge line.

A reverse sequence of operations occurs in breaking a pipe joint. First the tongs are applied to the pipe and the mounts 40 and 55 thrust fully forward under pressure communicated through line 84 to cause the dies 44, 28 and 44a, 31 to individually grip the pipe sections. At this time the spinner wheel 62, which may not be in operation, is pressed against the pipe by the thrust of spring 48. The piston and cylinder assembly 56 is operated to produce sufficient relative rotation of the tong sections 11 and 12 to initially break or loosen the joint to an extent that the upper pipe stand then may be turned out of the joint by the spinner wheel 62. The operating fluid there is communicated to cylinders 45 and 52 through line 75a and the regulator 75b, the pressure then being reduced sufficiently to disengage the dies from gripping relation with the pipe, but with the spinner wheel remaining in contact with the upper stand. The spinner then is driven in a direction such as to turn the upper pipe stand out of the joint.

It will be understood that the drawings are to be regarded merely as illustrative of the invention in one of its typical embodiments, and that various changes and modifications may be made without departure from the invention in its intended spirit and scope.

We claim:

1. A unitary pipe tongs assembly comprising upper and lower body sections having aligned recesses providing openings through which the pipe may enter said recesses upon bodily movement of the tongs transversely of the pipe, each of said sections including a lever extending outwardly from the recess, a connection between the sections maintaining said recesses in axial alignment and supporting one section by the other section while permitting relative oscillation thereof about the pipe axis, pipe gripping means carried by each section, and an actuating mechanism car-

ried by said assembly and connected to outer portions of said levers radially beyond said connection and operable to effect said relative oscillation of the sections.

5 2. A unitary pipe tongs assembly comprising upper and lower body sections having aligned recesses providing openings through which the pipe may enter said recesses upon bodily movement of the tongs transversely of the pipe, each 10 of said sections including a lever extending outwardly from the recess, said sections and levers being spaced apart longitudinally of the pipe, a connection between the sections and within the space between them for supporting one section by the other section and maintaining said recesses in axial alignment while permitting relative oscillation thereof about the pipe axis, pipe gripping means carried by each section, and an actuating mechanism carried by said assembly and connected to outer portions of said levers radially beyond said connection and operable to effect said relative oscillation of the sections.

15 3. A unitary pipe tong assembly comprising upper and lower body sections having aligned recesses to receive a pipe, means on the sections 25 providing lateral openings through which the pipe may enter said recesses upon bodily movement of the tongs transversely of the pipe, each of said sections including a lever extending outwardly from the recess, a connection between the sections maintaining said recesses in axial alignment and supporting one section by the other section while permitting relative oscillation thereof about the pipe axis, pipe gripping means carried by each section, and fluid pressure actuated means 30 carried by said assembly and connected to outer portions of said levers radially beyond said connection to positively produce relative swinging of the levers in opposite directions.

40 4. A unitary pipe tongs assembly comprising upper and lower body sections having recesses to receive a pipe, means on the sections providing lateral openings through which the pipe may enter said recesses upon bodily movement of the tongs transversely of the pipe, each of said sections 45 including a lever extending outwardly from the recess, a connection between said sections maintaining said recesses in axial alignment and supporting one section by the other section while permitting relative oscillation thereof about the pipe axis, said sections presenting a pair of pipe 50 engaging surfaces aligned longitudinally of the pipe at said recesses, pipe gripping means carried by each section, power units carried by each section and operable to actuate said gripping means to press the pipe against said aligned surfaces, and fluid pressure actuated means carried by said assembly and connected to outer portions of the levers radially beyond said connection and operable to positively produce relative 55 swinging of the levers in opposite directions.

5. A unitary pipe tongs assembly comprising upper and lower body sections having aligned recesses to receive a pipe, means on the sections 60 providing lateral openings through which the pipe may enter said recesses upon bodily movement of the tongs transversely of the pipe, each of said sections including a lever extending outwardly from the recess, interlocking elements on the respective sections maintaining said recess in axial alignment and supporting one section by the other section while permitting relative oscillation thereof about the pipe axis, said connection also maintaining the recessed portions of the 65 sections in substantial parallelism during their

oscillation, pipe gripping means carried by each section, fluid pressure actuated power sources carried by said sections for operating said gripping means, fluid pressure actuated means carried by outer portions of said levers radially beyond said elements and operable to effect said relative oscillation of the sections, and valve means operable to selectively control the delivery of pressure fluid to said power sources and fluid pressure actuated means.

6. A unitary pipe tongs assembly comprising upper and lower body sections having alined recesses to receive a pipe, means on the sections providing lateral openings through which the pipe may enter said recesses upon bodily movement of the tongs transversely of the pipe, each of said sections including a lever extending outwardly from the recess, interlocking elements on the respective sections maintaining said recesses in axial alinement and supporting one section by the other section while permitting relative oscillation thereof about the pipe axis, pipe gripping means carried by each section, fluid pressure actuated power sources carried by said sections for operating said gripping means, fluid pressure actuated means carried by said assembly and connected to outer portions of said levers to effect said relative oscillation of the sections, a fluid control valve assembly carried by one of said sections, fluid conduits connecting said valve assembly with said fluid pressure actuated means and the power source carried by the last mentioned section, and a flexible fluid conduit connecting said valve assembly with the power source carried by the other section.

7. A unitary pipe tongs assembly comprising upper and lower body sections having alined recesses to receive a pipe, means on the sections providing lateral openings through which the pipe may enter said recesses upon bodily movement of the tongs transversely of the pipe, each of said sections including a lever extending outwardly from the recess, a connection between the sections maintaining said recesses in axial alinement and supporting one section by the other section while permitting relative oscillation thereof about the pipe axis, pipe gripping means carried by each section, fluid pressure actuated means carried by said assembly and connected to outer portions of said levers to effect said relative oscillation of the sections, and means connected to said upper section for suspending the tongs so that said lower section is suspended from the upper section and is movable relative to said suspension means.

8. A unitary pipe tongs assembly comprising upper and lower body sections having alined recesses providing openings through which the pipe may enter said recesses upon bodily movement of the tongs transversely of the pipe, each of said sections including a lever extending outwardly from the recess, interlocking elements on the respective sections maintaining said re-

cesses in axial alinement and supporting one section by the other section while permitting relative oscillation of the sections about the pipe axis, pipe gripping means carried by each section, fluid pressure actuated power sources carried by said sections for operating said gripping means, fluid pressure actuated means carried by said assembly and connected to outer portions of said levers to effect said relative oscillation of the sections, a fluid control valve assembly, and fluid conduits connecting said valve assembly with said power sources and fluid pressure actuated means, said valve assembly being operable to selectively actuate said power sources and fluid pressure actuated means.

9. A unitary pipe tongs assembly comprising upper and lower body sections having alined recesses providing openings through which the pipe may enter said recesses upon bodily movement of the tongs transversely of the pipe, each of said sections including a lever extending outwardly from the recess, interlocking elements on the respective sections maintaining said recesses in axial alinement for reception of the pipe and supporting one section by the other section while permitting relative oscillation of the sections about the pipe axis, pipe gripping means carried by each section, fluid pressure actuated power sources carried by said sections for operating said gripping means, fluid pressure actuated means carried by said assembly and connected to outer portions of said levers to effect said relative oscillation of the sections, a rotatable element carried by the tongs and engageable with the pipe to rotate same, a fluid motor for rotating said element, a fluid control valve assembly, and fluid conduits connecting said valve assembly with said power sources, fluid pressure actuated means and fluid motor, said valve assembly being operable to selectively actuate said power sources, fluid pressure actuated means and fluid motor.

Certificate of Correction

Patent No. 2,453,369.

November 9, 1948.

DONOVAN B. GRABLE ET AL.

It is hereby certified that errors appear in the printed specification of the above numbered patent requiring correction as follows:

Column 6, line 23, claim 3, for "tong" read *tongs*; line 25, same claim; lines 41 and 42, claim 4; line 64, claim 5; column 7, line 13, claim 6; line 38, claim 7, strike out the words "to receive a pipe, means on the sections"; column 6, line 26, claim 3; line 43, claim 4; line 65, claim 5; column 7, line 14, claim 6; line 39, claim 7, strike out "lateral"; column 6, line 70, claim 5, for "recess" read *recesses*;

and that the said Letters Patent should be read with these corrections therein that the same may conform to the record of the case in the Patent Office.

Signed and sealed this 15th day of March, A. D. 1949.

[SEAL]

THOMAS F. MURPHY,
Assistant Commissioner of Patents.
